CLAIM

The ornamental design for a dosing container as shown and described.

DESCRIPTION

FIG. 1 is a front left side perspective view showing the new design of a dosing container;

FIG. 2 is a rear right side perspective view from underneath thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front left side perspective view showing the new design for a dosing container from FIG. 1 and illustrating a partial removal of a dosing cap;

FIG. 10 is a rear right side perspective view from underneath thereof;

FIG. 11 is a front view thereof;

FIG. 12 is a rear view thereof;

FIG. 13 is a left side view thereof;

FIG. 14 is a right side view thereof;

FIG. 15 is an exploded front left side perspective view showing the new design for a dosing container from FIG. 1 and illustrating a removal of a dosing cap;

FIG. 16 is an exploded rear right side perspective view from underneath thereof;

FIG. 17 is an exploded front view thereof;

FIG. 18 is an exploded rear view thereof;

FIG. 19 is an exploded left side view thereof;

FIG. 20 is an exploded right side view thereof;

FIG. 21 is an exploded top plan view thereof; and,

FIG. 22 is an exploded bottom plan view thereof.

The evenly spaced broken lines shown in the drawings illustrate portions of the dosing container that form no part

(Continued)

of the claimed design. The dot-dash lines shown represent exploded reference lines and form no part thereof.
